HENRY W. LLOYD, OF NEW YORK, N. Y., ASSIGNOR TO F. C. DAVIDGE & CO., OF TORONTO, CANADA.

DESIGN FOR WALL-PAPER.

No. 38,173.

Specification for Design.

Patented Aug. 14, 1906.

Application filed June 5, 1906. Serial No. 320,344. Term of patent 3½ years.

To all whom it may concern:

Be it known that I, HENRY W. LLOYD, a subject of the King of Great Britain, residing at New York, in the county of New York and State of New York, have invented a new, original, and ornamental Design for Wall-Paper, of which the following is a specification, reference being had to the accompanying drawing, forming part thereof.

The nature of the design is fully represented in the drawing, which shows in elevation a section of my wall-paper design.

I claim—

The ornamental design for wall-paper, as shown.

HENRY W. LLOYD.
